COAGULYZER REACTION CUVETTE

David Alan Ritchie, St. Louis, Mo., assignor to Sherwood
Medical Industries Inc., St. Louis, Mo.

Filed Jan. 20, 1971, Ser. No. 108,257

Term of patent 14 years

Int. Cl. D24—02

U.S. Cl. D16—1

FIG. 1

FIG. 2

FIG. 3

FIG. 4

FIG. 1 is a front perspective view of a coagulyzer reaction cuvette showing my new design;

FIG. 2 is a cross-section taken on line 2—2 of FIG. 3;

FIG. 3 is a side elevational view of the coagulyzer reaction cuvette illustrated in FIG. 1; and

FIG. 4 is a rear bottom perspective view of the coagulyzer reaction cuvette.

I claim:

The ornamental design for a coagulyzer reaction cuvette, as shown and described.
